SLIPPER AND METHOD OF MAKING SAME

George P. Naidor, New York, N. Y.

Application May 9, 1934, Serial No. 724,637

8 Claims. (Cl. 12—142)

This invention relates to improvements in slippers and more particularly to the soft-soled type of slipper and the method of making the same.

My Patent Number 1,916,067, dated June 27, 1933, discloses a slipper in which the upper, sole and sock lining are secured together by a row of stitching and a padding inserted between the sole and lining. Some difficulty has been experienced in introducing the padding into the space between said sole and lining. In accomplishing this operation a pronged implement has been employed to force the padding into position. It has been found that the prongs of said implement have a tendency to displace the fibers of the padding and cause the same to bunch in the toe of the slipper so that an uneven surface is formed.

The present invention is designed primarily to overcome the above difficulty by providing the padding with a pocket into which a flat implement may be inserted and engaged with the toe end of the padding so that the latter can be readily forced into the space between the sole and sock lining and positioned therein in a perfectly flat condition.

The invention further contemplates a padding in which two superimposed layers of material are secured together for portions of the lengths thereof, with the remaining portions unattached to each other so that the shank stiffener of the slipper may be positioned between the latter portions with one of them thus overlying the stiffener and interposed between the same and the foot of the wearer.

The inventive idea involved is capable of receiving a variety of expressions one of which, for purposes of illustration, is shown in the accompanying drawing, wherein:

Figure 1 is a longitudinal section through a completed slipper constructed in accordance with the invention.

Figure 2 is a similar section showing the slipper at an intermediate stage of assembly.

Figure 3 is a top plan view, partly broken away and shown in section, with the upper portion of the padding turned back so as to disclose the shank stiffener of the shoe.

Figure 4 is a section on the line 4—4 of Figure 1.

Figure 5 is a section on the line 5—5 of Figure 1, and

Figure 6 is a perspective view of the padding of the slipper.

In assembling the elements of the slipper, the same initial procedure is followed as set forth in the above-noted patent. That is, the upper 7,

the soft sole 8 and the sock lining 9 are first brought together in a reversed position from that shown in Figures 1 and 2 of the present drawing, and with the sole on the under side of the upper and the sock lining on the opposite side. The 5 outer edges of said three elements are then stitched together by a single row of stitches 10 and such stitches are extended rearwardly to approximately the medial point of the slipper as indicated at 11 (Figure 2). Also, as in the above 10 patent, the row of stitching is continued rearwardly from the point 11 to secure the upper to the sole, leaving the rear portion of the sock lining free. Following this stitching operation the elements 7, 8, and 9 are turned inside out to their 15 normal positions shown in Figure 2.

The padding generally indicated by the numeral 12 is then inserted into the space between the sole 8 and the sock lining 9. In order to facilitate the insertion of said padding the same, 20 in accordance with the present invention, is made of two superimposed layers 13 and 14 of fibrous material usually employed in slippers of this character. Said layers are of sufficient length to cover the entire interior of the slipper and are secured 25 together by stitching along their edges from the toe end of the padding to a point intermediate the ends thereof as indicated at 15. The remainder or rear portions of the layers 13 and 14 thus remain unattached and provide an opening at the 30 intermediate point of the padding for the insertion of a flat implement into the pocket formed by the attached forward portions of said layers. With said implement thus inserted into the pocket and engaged with the toe end of the padding, 35 the latter may be introduced into the space between the sole 8 and lining 9 and forced forwardly by pressure of said implement until the toe end of the padding contacts the tip of the slipper. The padding is thus enabled to be maintained 40 in a flat condition so that it will not wrinkle in the toe portion of the slipper and after it has been properly positioned the implement used to force the same into place may be withdrawn.

The next operation in the assembly of the 45 parts of the slipper is to lay the shank stiffener 16 in position and secure the same to the heel 17 of the slipper by the fasteners 18. The shank stiffener 16 is laid upon the rear portion of the lower layer 14 of the padding 12 and after being secured by said fasteners 18, the rear portion of the upper material 13 of said padding is then superimposed upon the shank stiffener so that the latter will be positioned between the two layers of the padding and the wearer's foot 55

thus adequately protected against any possible contact with said shank stiffener. It is also proposed to encase the rear portion of the upper layer 13 of the padding within the sock lining layer 14 and, for this purpose, an additional strip 19 5 of the same material as the sock lining is stitched thereto so as to form a pocket for receiving said portion of the padding. Said strip 19 extends forwardly from the heel to approximately the point 15 where the two layers of the padding are secured together and as a final operation in the assembly of the parts of the slipper, a suitable adhesive is applied to the under surface of said strip 19 so that it will adhere to the rear portion 10 of the layer 14 of the padding and to the shank 16 which is superimposed upon said portion.

What is claimed is:

1. The method of making slippers which comprises securing together the upper, sole and sock lining of a slipper while said elements are in a reversed position with the upper interposed between the sole and sock lining, turning said elements to their normal position, supplying a padding formed of two layers of material stitched together partly around their edges to provide a pocket, and forcing said padding between said lining and sole by utilizing an implement introduced into said pocket.
2. The method of making slippers which comprises assembling the upper, sole and sock lining of a slipper, securing less than the entire length of said lining to said upper by a row of stitches passing through all three of said elements, continuing said row of stitches to attach the remaining length of the sole to said upper, supplying a padding formed of two layers of material stitched together partly around their edges to form a pocket, and forcing said padding between said lining and sole by inserting an implement into said pocket.
3. The method of making slippers which comprises securing together the upper, sole and sock lining of a slipper while said elements are in a reversed position with the upper interposed between the sole and sock lining, turning said elements to their normal position, supplying a padding

5 ding formed of two layers of material stitched together partly around their edges to provide a pocket, forcing said padding between said lining and sole by utilizing an implement introduced into said pocket, and encasing an unstitched part 5 of said padding within a portion of said lining.

4. A slipper comprising an upper, a sole, a sock lining, means securing all three of said elements together, and a padding inserted between said sole and lining and having a pocket therein 10 the closed end of which terminates at the toe portion of the padding.

5. A slipper comprising an upper, a sole, a sock lining, means securing all three of said elements together, and a padding inserted between 15 said sole and lining, said padding consisting of two superimposed layers of material the forward portions of which have their edges secured together and the rear portions being unattached.

6. A slipper comprising an upper, a sole, a 20 sock lining, means securing all three of said elements together, a padding inserted between said sole and lining, said padding consisting of two superimposed layers of material the forward 25 portions of which have their edges secured together, and the rear portions being unattached, and said sock lining having a recess for receiving and enclosing one of the rear portions of said padding.

7. A slipper comprising an upper, a sole, a 30 sock lining, means securing all three of said elements together, a padding inserted between said sole and lining, said padding consisting of two superimposed layers of material the forward 35 portions of which have their edges secured together and the rear portions being unattached, said sock lining having a recess for receiving and enclosing one of the rear portions of said padding, and a shank stiffener positioned between said rear portions of said padding. 40

8. A padding for use in slippers and adapted for insertion between the sole and sock lining of a slipper, said padding comprising two layers of material the edges of which are secured together for only a portion of the total length of 45 the padding.

GEORGE P. NAIDOR.
